UNITED STATES PATENT OFFICE.

JAMES J. CHARVAT, OF CHICAGO, ILLINOIS.

STOPPER-EXTRACTOR.

1,086,645.

Specification of Letters Patent. Patented Feb. 10, 1914.

Application filed July 3, 1913. Serial No. 777,288.

To all whom it may concern:

Be it known that I, JAMES J. CHARVAT, a citizen of the United States, residing at Chicago, in the county of Cook and State of Illinois, have invented certain new and useful Improvements in Stopper-Extractors, of which the following is a specification.

This invention relates to devices for removing the paper caps of milk bottles, and its object is to provide a simple and efficient device of this kind, by which the cap can be easily removed, and replaced if desired.

In the accompanying drawing forming a part of this specification, Figure 1 is a perspective view of the device, and Fig. 2 is an edge view thereof. Fig. 3 is a plan view of the blank out of which the device is made.

As shown in the drawing the device comprises a flat plate 5, slightly elongated, and having at its forward end a sharp prong 6 and at its rear end a prong 7. To facilitate the operation of the device, the plate 5 is provided with a suitable handle 8. The prong 6 extends outward in a straight line and it is formed integral with the plate 5. The prong 7 is also formed integral with the plate 5 by slitting the same to form a pointed tongue, and bending the tongue downward from the plate. The last-mentioned prong projects sidewise from the plate.

In operation, the plate 5 is grasped by its handle 8 and the prong 6 is stuck into the cap to be removed. The rear end of the plate is then pressed downward with a lateral twist to stick the prong 7 into the cap, after which the cap can be pulled off its seat. It will be noted that the edge of the plate

5, adjacent to the prong 7, forms a shoulder 9 from which shoulder said prong is downwardly offset. Thus, when the prong 7 is stuck into the cap and the plate 5 is given a slight turn or twist, the cap is gripped between said prong and the shoulder 9, and when the cap is removed from its seat, it will not drop off the device. If the cap is to be replaced, a slight twist backward will remove it from the device. The prongs 6 and 7, being sharp, readily enter the cap, and it is not necessary to bear down heavy on the cap, which is liable to push the cap into the bottle if wet and soft.

The device is formed out of a sheet of suitable metal which is slotted as indicated at 10 in Fig. 3, said slit conforming to the outline of the forward portion of the device and the prong 6. The material, forward of the slit, is then bent to extend perpendicular to the sheet to form the handle 8, the same being provided with a perforation 11.

I claim:

A stopper extractor comprising a plate having a slotted portion shaped to form an outstanding prong, the plate on one side of the slit being bent perpendicular to form a handle, and the rear end of the plate having a laterally projecting, downwardly pointing prong.

In testimony whereof I affix my signature in presence of two witnesses.

JAMES J. CHARVAT.
